ATTORNEY

UNITED STATES PATENT OFFICE.

WALDEMAR F. MAYER, OF PHILADELPHIA, PENNSYLVANIA, ASSIGNOR TO TAYLOR-WHARTON IRON AND STEEL COMPANY, OF HIGH BRIDGE, NEW JERSEY, A CORPORATION OF NEW JERSEY.

MACHINE-TOOL CONTROL.

1,352,673.

Specification of Letters Patent. Patented Sept. 14, 1920.

Application filed June 27, 1919. Serial No. 307,161.

To all whom it may concern:

Be it known that I, WALDEMAR F. MAYER, a citizen of Switzerland, residing at Philadelphia, in the county of Philadelphia and 5 State of Pennsylvania, have invented certain new and useful Improvements in Machine-Tool Control, of which the following is a specification.

The principal objects are to provide for 10 operating and controlling machine tools, such as lathes, boring mills, milling machines, and the like, by means of fluid gears or so-called hydraulic transmissions; to prevent overloading of the prime mover, 15 usually an electric motor; to provide for limiting the tool pressure so as not to spoil the tool; and to control the speed within or below the limits determined by these requirements.

20 With such and other objects in view, the nature, characteristic features and scope of the invention will more readily be understood from the following description taken in connection with the accompanying drawings, forming a part hereof, wherein—

Figure 1 is a side elevational view, partly in section, of the headstock portion of a roll lathe embodying my invention.

Fig. 2 is a view principally in section of 30 control members of the hydraulic transmission.

Fig. 3 is a section on line 3—3 of Fig. 2.

In the illustrated embodiment of my invention applied to a roll lathe, 1 designates 35 the face plate supported on a spindle 2 and having an internal gear 3, which meshes with a pinion 4. The latter is keyed to the driving shaft of a hydraulic engine 5, which is driven in the well known manner 40 by fluid pressure supplied by a reversible variable fluid delivery pump 6. The fluid supply and return connections are indicated, respectively, at 7 and 8. The pump is driven preferably at constant speed in any 45 suitable manner, for example, by an electric motor 9, a coupling being indicated at 10. In lieu of the coupling, a gear or clutch connection may be employed and as they are of well known and usual construction 50 it has not been deemed necessary to illustrate them.

The electric motor or other prime mover, pump, hydraulic engine, and face plate spindle are supported or carried by a casting 11, which is bolted onto a bed-plate 12. 55 The casting 11 also supports a spring-loaded adjustable safety valve 13 located in the fluid line between the pressure and discharge sides.

The rate of delivery of the pump is positively controlled by a lever 14, and since the speed of the hydraulic engine depends upon the rate of fluid flow through the pump and engine, the position of lever 14 determines one certain lathe speed.

The differential valve 13 is mounted in a housing 16 and normally separates the working fluid passages 7 and 8. The valve stem 17 is equipped with spring washers 18, one of which bears against a shouldered portion of the stem, and the other against an adjusting member or nut 19. The compression spring 20 between the washers is capable of adjustment by means of said nut, for example, through the instrumentality of a screw-threaded cap 21, its hand-wheel 22, and a cap-plate 23, which engages the nut. The housing 16 and the valve-stem 17 have the same number of screw-threads per inch so that the parts can be adjusted with precision, and the spindle 17 is secured against rotation, to admit of said adjustment, by means of a slot 24 and key 25.

The movement of speed control lever 14 is limited in one direction by a chain 26, 85 one end of which is fastened to the lever, as at 27, and the other end of which is connected to a loose ring or swivel 28 on the cap 21.

Since an electric motor or any other prime 90 mover has a limited power capacity, it is essential for efficient operation that the variable hydraulic speed gear should be of such design that it will offer more resistance than the prime mover can overcome.

The power of the hydraulic engine is the product of its torque, determined by fluid pressure, and of its angular speed, determined by the position of the control lever 14. Therefore, speed and pressure have to 100 be coördinated for constant horsepower output. It is evident that for high fluid pres-

sure the speed is low, and for low fluid pressure the speed is high.

The pressure limitation is governed by the tension of the safety valve spring 20.

5 Let us assume that the pressure side is 7 and that the discharge is at 8. Pressure is applied to the larger valve disk 29 through a channel 30, and to the smaller disk 31 through a channel 32, so that the differential 10 valve is under pressure from opposite directions. The variance in pressure as between the two disks is transmitted to the spring 20, which has a certain initial compression set by the hand-wheel 22. If the resultant 15 valve pressure exceeds the initial spring compression the valve will move outward and continue to compress the spring until passage 30 is in communication with passage 33, the effect of which is to by-pass fluid 20 from the pressure side 7 to the discharge side 8 and to stop the hydraulic engine and consequently the face-plate. The pressure cannot increase while the safety valve is bypassing fluid. Hence, a constant predetermined 25 tool pressure exists and no harm can befall the tool.

The speed is determined by the position of the control lever 14. Referring to Fig. 2, the solid line illustration of the lever 30 corresponds to a certain predetermined cutting speed position. The dotted line illustration 141 indicates zero speed (stop) and the illustration 142 indicates reverse speed. The rate of speed increases gradually from zero speed position 141 as the lever is moved farther and farther away from that position. The by-pass pressure increases gradually as the spring 20 is compressed gradually by the hand-wheel 22.

40 The lever restraining element or chain 26 will not permit excessive speed even though the by-pass pressure is adjusted for a high value, because the stretched position of the chain always corresponds to the maximum 45 transmitted horsepower. Hence, the chain acts as a safeguard to prevent overloading of the prime mover.

The adjustment of the spring 20 depends upon the nature of the tool and the diameter 50 of the work.

The fluid pressure being proportional to torque, which in turn depends on tool pressure and diameter of work, these values should be determined by practice and tabulated for use as a guide to the operative.

55 With the by-pass pressure adjusted to protect the tool, the operator may run the lathe within the speed limit which corresponds to that pressure at the maximum 60 horsepower.

Having described the nature and objects of the invention, I claim:—

1. A machine tool control, comprising the combination of a member adapted to be 65 driven at different speeds, fluid means for

driving it, a prime mover, and means co-operating with said fluid means for co-ordinating speed and tool pressure within predetermined limits.

2. A machine tool control, comprising 70 the combination of a member adapted to be driven at different speeds, a prime mover, and a fluid gear connecting it with said member and including means for maintaining a constant predetermined tool pressure. 75

3. A roll lathe control, comprising the combination of a face plate, a prime mover, a fluid gear connecting the prime mover and face plate, and means inter-related with the fluid gear for limiting the tool pressure and for controlling the speed. 80

4. A roll lathe control, comprising the combination of a face plate, a prime mover, a hydraulic transmission interposed between the prime mover and face plate and comprising a reversible variable fluid delivery pump, a hydraulic engine, and their complemental fluid connections, and means for controlling the delivery of the pump. 85

5. A roll lathe control, comprising the 90 combination of a face plate, a prime mover, a hydraulic transmission interposed between the prime mover and face plate and comprising a reversible variable fluid delivery pump, a hydraulic engine, and their complemental fluid connections, means for controlling the delivery of the pump, and a limit device for said means. 95

6. A roll lathe control, comprising the combination of a face plate, a prime mover, 100 a hydraulic transmission interposed between the prime mover and face plate and comprising a variable and reversible fluid delivery pump, a hydraulic engine, and their complemental fluid connections, and means for controlling the delivery of the pump and having an initial predetermined cutting speed. 105

7. A roll lathe control, comprising the combination of a face plate, a prime mover, 110 a hydraulic transmission operatively connecting the prime mover and face plate and comprising a variable and reversible fluid delivery pump, a hydraulic engine, and their complemental fluid connections, and means 115 for controlling the delivery of the pump and movable from a predetermined cutting speed position through zero speed to reverse speed.

8. A roll lathe control, comprising the 120 combination of a face plate, a prime mover, a hydraulic transmission operatively connecting the prime mover and face plate and comprising a variable and reversible fluid delivery pump, a hydraulic engine, and their complemental fluid connections, and means for controlling the delivery of the pump and movable from a predetermined cutting speed position through zero speed 125 to reverse speed and the extreme position 130

of which corresponds to the maximum transmitted horsepower.

9. A roll lathe control, comprising the combination of a face plate, a prime mover, 5 a hydraulic transmission operatively connecting the prime mover and face plate and comprising a variable and reversible fluid delivery pump, a hydraulic engine, and their complemental fluid connections, a 10 safety valve in the fluid line, and means for controlling the delivery of the pump within the limits fixed by said valve.

10. A roll lathe control, comprising the combination of a face plate, a prime mover, 15 a hydraulic transmission operatively connecting the prime mover and face plate and comprising a variable and reversible

fluid delivery pump, a hydraulic engine, and their complemental fluid connections, control mechanism, and a common support for 20 all of said elements.

11. A roll lathe control, comprising the combination of a face plate, a prime mover, a hydraulic transmission operatively connecting the prime mover and face plate and comprising a variable and reversible fluid delivery pump, a hydraulic engine, and their complemental fluid connections, a safety valve in the fluid line, means for controlling the delivery of the pump within the limits fixed by said valve, and a check on said means independent of the valve.

In testimony whereof I affix my signature.
WALDEMAR F. MAYER.
